CLAIM

The ornamental design for a broom head, as shown and
described.

DESCRIPTION

FIG. 1 is a top plan view of a broom head showing our
new design;

FIG. 2 is a side view of the broom head shown in FIG.
1, the side opposite to that shown in FIG. 2 being the
same in appearance as that shown in FIG. 2;

FIG. 3 is an end view of the broom head shown in FIG.
1, the end opposite to that shown in FIG. 3 being the
same in appearance as that shown in FIG. 3; and

FIG. 4 is a bottom plan view of the broom head shown
in FIG. 1.
